UNITED STATES PATENT OFFICE.

CHARLES C. KOEHL, OF PATERSON, NEW JERSEY.

BOOK-REST AND MANUSCRIPT-HOLDER.

SPECIFICATION forming part of Letters Patent No. 269,683, dated December 26, 1882.

Application filed June 2, 1882. (No model.)

To all whom it may concern:

Be it known that I, CHARLES C. KOEHL, of Paterson, in the county of Passaic and State of New Jersey, have invented a new and Improved Book-Rest and Manuscript-Holder, of which the following is a full, clear, and exact description.

The object of my invention is to provide a new and improved device for holding books or papers and for forming a reading-mark and eye-protector.

The invention consists in a plate provided with springs for holding a book, and with a curtain attached to a suitable roller or shaft, which curtain is used to cover that part of the book or sheet that has been read, and thus forms a book-mark and an eye-protector.

The invention also consists in certain details of construction, hereinafter more fully set forth, and pointed out in the claims.

Reference is to be had to the accompanying drawings, forming part of this specification, in which similar letters of reference indicate corresponding parts in all the figures.

Figure 1 is a perspective view of my improved book-rest and reading-mark. Fig. 2 is a front elevation of the same. Fig. 3 is a side elevation of the same, showing it attached to a standard. Fig. 4 is a longitudinal sectional elevation of the same. Fig. 5 is a longitudinal sectional elevation of the binding-screw socket on the back of the book-rest, showing the position of the screw when locking the supporting-frame in position. Fig. 6 is a longitudinal sectional elevation of the same, showing the position of the screw when locking the book-rest to the upper transverse rod or arm of a standard.

The plate A, made of wood, metal, pasteboard, or any other suitable material, is provided at its lower edge with two clamping-springs, B, for holding the lower edge of a book or sheet. At the upper end it is provided with one or more side-clamping springs, C, for holding the side edges of a book or sheet. The plate A is provided near its upper end and on its rear side with a jaw, D, at each longitudinal edge, and in these jaws a transverse shaft or roller, E, is journaled, which is provided with a knob or button, F, on one projecting end. A cur-

tain, G, is attached to this roller or shaft and passes under a rod, H, held parallel with the upper edge of the plate A, a short distance above the same, and over a rod, I, held above the rod H and outside of the plane of the upper or front surface of the plate A—that is, the rod I is diagonally above and in front of the rod H. The free end of the curtain is attached to a weighted transverse rod, J. This plate A is provided on its rear side with an internally-threaded tubular projection, K, into which a binding-screw, L, is screwed. This tubular projection is provided with two transverse horizontal apertures, a b, near the inner and outer ends of the projection, respectively.

A supporting-frame, M, is hinged to the back of the plate A, and the upper cross-piece of this supporting-frame passes through the inner aperture, a. A U-shaped spring-clamp, N, into which one of the shanks of the frame M passes when it is folded against the back of the plate A, serves to lock this frame M against the back of the plate. The supporting-frame M can be placed at any desired inclination to the back of the plate A and be locked in the desired position by the binding-screw L, which presses against the upper cross-piece of the frame M, as shown in Fig. 5.

If the plate A is to be secured to the horizontal arm O of a standard, P, the binding-screw L is unscrewed sufficiently to permit the arm O to be passed through the outer transverse aperture, b, and the plate A is locked on this arm at the desired inclination by means of the binding-screw L, which presses against this arm O, as shown in Fig. 6. The curtain G is drawn over those parts of the book that have been read, and thus forms a reading-mark and an eye-protector, for a person can immediately find the last line that has been read, as those lines that have been read are successively covered by drawing down the curtain. This relieves the nervous system and avoids undue straining of the eyes, and saves time in finding the last line read. This is of great convenience, especially for orators, lecturers, compositors, and others who must frequently refer to notes during their discourse. By turning the shaft or roller E by means of the button F the curtain can be wound on this roller, so as

to be entirely out of sight from the front of the plate. In the same manner as the plate is fastened to the arm O of the standard P it can be attached to any other like rod or arm.

5 The book-rest can be easily adjusted in any desired position, as may be required, and can be made more or less ornamental. If not used as a book-rest, it can be used as an easel for holding pictures, cards, &c.

10 Having thus fully described my invention, I claim as new and desire to secure by Letters Patent—

1. In a book-rest, the combination, with the plate A, of the shaft or roller E and the curtain G, attached to this shaft or roller, substantially as herein shown and described, and for the purpose set forth.

2. In a book-rest, the combination, with the plate A, of the shaft or roller E F, the curtain G, attached to the same, and the guide-wires 20 H and I at the upper end of the plate A, substantially as herein shown and described, and for the purpose set forth.

3. In a book-rest, the combination, with the plate A, provided with U-shaped spring catch 25 N and tubular projection K, having transverse apertures a b, of the hinged supporting-frame M and binding-screw L, substantially as and for the purpose set forth.

CHARLES C. KOEHL.
